UNITED STATES PATENT OFFICE.

HERMAN M. BIEBEL, OF OAKMONT, PENNSYLVANIA, ASSIGNOR TO WESTINGHOUSE ELECTRIC & MANUFACTURING COMPANY, A CORPORATION OF PENNSYLVANIA.

INDICATING FLUID-CIRCUIT INTERRUPTER.

Application filed May 10, 1922. Serial No. 559,691.

My invention relates to circuit interrupters and particularly to fluid circuit interrupters and it has for its object to provide a relatively simple and compact fluid circuit interrupter that shall embody means for luminously indicating that the circuit has been interrupted.

In practicing my invention, I provide a closed evacuated tube of transparent insulating material in which is placed a conducting fluid and a quantity of neon gas. A plurality of electric circuit terminals project into the tube in spaced-apart relation.

In the single sheet of drawings, Figure 1 is a view, in side elevation, of an electrically heated iron, with which is associated the device embodying my invention, certain portions of the iron being cut away;

Fig. 2 is a diagrammatic representation of an electrically heated apparatus, with which is associated the device embodying my invention;

Fig. 3 is a top plan view of a modified form of the device embodying my invention;

Fig. 4 is a view, in side elevation, of the device illustrated in Fig. 3.

An electric iron, designated generally by the numeral 11, comprises a sole plate 12, a heating element 13, a top plate 14 and a cover member 15. The top plate and the heating element are clamped against the sole plate by a plurality of bolts 16, only one of which is illustrated in the drawing. The cover 15 is held in its proper operative position by a single bolt 17. A handle member 18 is supported by the top ends of two handle straps 19 and 21, the lower ends of which are secured against the cover member 15 by rivets 22. As the electric heating element 13 is not a part of my invention it is not deemed necessary to describe it in detail as it may be of any suitable type usually employed in the art. The terminals of the resistor of the heating element may be suitably connected to upwardly extending terminal straps 23 which may be held in place by a terminal-supporting member 24 which is, in turn, held in its proper operative position by the rear bolt 16.

A terminal casing 25 is located at the rear of the iron and is suitably secured in its proper operative position by any suitable means. It is provided with a sight

opening 26 which may be left open or closed by a suitable transparent plate 27. A supply-circuit conductor 28 of the usual construction is provided, which extends into the terminal casing 25, a helical spring 29 being provided in order to prevent undue kinking of the conductor 28.

A fluid circuit interrupter 31, which may be of the type disclosed and claimed in co-pending application, Serial No. 503,796, filed by O. A. Colby, September 28, 1921, and assigned to the Westinghouse Electric & Manufacturing Co., may be located within the casing 25. The circuit interrupter 31 comprises a closed evacuated tube 32 of transparent insulating material, such as glass or quartz, and is of substantially U-shape, one leg thereof being substantially shorter than the other. The tube 32 is filled with a quantity 33 of a suitable conducting fluid, such as mercury, and a plurality of spaced-apart electric circuit terminals 34 extend into the tube and operatively engage the column of conducting fluid. I place in the tube 32 also a quantity of neon gas.

Figs. 3 and 4 illustrate a modification of the device embodying my invention in which the fluid circuit interrupter comprises a large tube 35, of substantially U-shape, and of a transparent insulating material, such as glass or quartz. Electric circuit terminals 34 extend into the tube at the ends thereof and operatively engage a quantity 33 of a suitable conducting fluid such as mercury. The device may be arranged for manual operation to interrupt or close the circuit and may be mounted on a suitable base 36 which is provided with upwardly extending lugs 37. A supporting means for the tube 35 may comprise a suitable metallic member 38 having portions adapted to clamp the tube 35 and having short shaft extensions 39 and 41 which are located in the upwardly extending lugs 37. A knob 100 or button 42 may be secured on the outer end of the extension 41 to permit of giving the tube 35 a turning movement. When the tube 35 is in substantially the position illustrated in Fig. 4 an electric circuit is established therethrough, the current flowing from one of the terminals 34 through the column 33 of conducting fluid to the other of the terminals. If the tube 35 is given a small angular turning movement in its

support so that the ends of the tube are lower, the column of conducting fluid will be broken in substantially the middle or intermediate portion of the tube and there-
 5 by interrupt the circuit. I have illustrated stop members 43 and 44 as means for limiting the turning movement of the tube in its support. I place in this tube, in addition to the conducting fluid, a small quantity of neon gas.
 10

If the circuit is interrupted, either manually or automatically, in the tube illustrated in Figs. 1 and 2 of the drawing, a portion of the conducting fluid is caused to be located
 15 in the shorter portion of the tube, and the conducting fluid will be disengaged from the upper of the two electric circuit wires 34. The neon gas will then be located in such position as to lie between the upper electric
 20 circuit terminal and the top of the column of conducting fluid and be subject to the potential of the circuit whereby it is caused to glow, thereby indicating that the circuit has been interrupted. In the modification
 25 of the device illustrated in Figs. 3 and 4, the neon gas occupies substantially the same position at all times but is subject to the electric potential of the circuit whenever the circuit has been interrupted in the tube
 30 35 and, therefore, will glow whenever it is subjected to the potential of the circuit, thus indicating an interrupted circuit. Such a tube thus operates as a space-current device to indicate an interruption of the circuit.
 35 The device embodying my invention thus

provides a relatively simple and compact circuit interrupter comprising embodying means for luminously indicating the interruption of the circuit.

I claim as my invention:

1. A circuit-interrupter comprising a closed transparent tube, a normally continuous column of conducting fluid therein, and neon gas in said tube for luminously indicating a break in said column of conducting fluid. 45

2. A circuit-interrupter comprising an initially evacuated closed transparent tube, a normally continuous column of conducting fluid and a relatively small quantity of neon gas in said tube, whereby said tube becomes 50 luminous upon the breaking of said column of conducting fluid.

3. A circuit-interrupter comprising a closed, transparent tube, a normally continuous column of conducting fluid therein, 55 and neon gas in said tube for luminously indicating a break in said column of fluid.

4. A circuit interrupter comprising a closed transparent tube having a pair of spaced terminals therein and containing neon 60 gas adapted to glow in response to certain potential differences between the terminals, and mercury within the tube for connecting the terminals and movable to break connection between the terminals. 65

In testimony whereof, I have hereunto subscribed my name this 6th day of May, 1922.

HERMAN M. BIEBEL.
